SMOKING PIPE

Ben Lieber, Brooklyn, N. Y., assignor to Knickerbocker Smoking Pipe Co. Inc., Brooklyn, N. Y., a corporation of New York

Application June 2, 1949, Serial No. 3,012

Term of patent 7 years

(Cl. D85—8)

To all whom it may concern:

Be it known that I, Ben Lieber, a citizen of the United States of America, residing at Brooklyn, county of Kings, and State of New York, have invented a new, original, and ornamental Design for a Smoking Pipe, of which the following is a specification, reference being had to the accompanying drawing, forming part thereof.

In the drawing,

Fig. 1 is a view of the right hand side of a smoking pipe, showing my new design.

Fig. 2 is an end view thereof.

Fig. 3 is a view of the left hand side thereof.

Fig. 4 is a top plan view thereof.

Fig. 5 is a bottom plan view thereof.

I claim:

The ornamental design for a smoking pipe, as shown.

BEN LIEBER.
